UNITED STATES PATENT OFFICE.

HARRY KATIMS AND EMIL WEINER, OF NEW YORK, N. Y.

DESIGN FOR A TEXTILE FABRIC.

Application filed August 23, 1927. Serial No. 23,188. Term of patent 3½ years.

To all whom it may concern:

Be it known that we, HARRY KATIMS and EMIL WEINER, citizens of the United States, residing at New York, in the county of New York and State of New York, have invented a new, original, and ornamental Design for a Textile Fabric, of which the following is a specification, reference being had to the accompanying drawing, forming part thereof.

The figure is a face view of a textile fabric showing our new design.

We claim:

The ornamental design for a textile fabric as shown.

In testimony whereof we have affixed our signatures.

HARRY KATIMS.
EMIL WEINER.
